UNITED STATES PATENT OFFICE.

ALBERT C. FISCHER, OF CHICAGO, ILLINOIS.

RAIL FILLER.

Application filed August 30, 1926. Serial No. 132,546.

My present invention relates in general to paving projects and has particular reference to a so-called rail filler for insulating the rails of street car tracks, as an example, 5 from the street paving in which they are imbedded, so as to compensate for expansion and contraction of the pavement as well as to deaden the sound of traffic over the rail and otherwise protect the installation from 10 wear and tear.

The salient features of the present invention are illustrated in the accompanying drawing, in which—

Figure 1 is a perspective view of a rail 15 with an adjacent paving structure, and illustrating the application of the invention; and

Figure 2 is a detailed perspective view of one of the filler members.

Figure 3 is a detailed perspective view of 20 a modified form of the invention.

Referring now to the drawing in detail, and for the purpose of illustration it may be considered that the rail, which in the present illustration happens to be of the flange type, 25 has the usual head A, base B and connecting web C. The space defined by these parts very often is simply filled in with the paving material so that the pavement and rail become a unitary structure, at least so far as 30 concerns any attempts in insulating the rail so as to deaden the sound of traffic over the tracks, compensating for expansion and contraction of the paving structure and otherwise improving the installation.

According to my invention I propose to 35 make up a sectional rail filler, so to speak, the same comprising a plurality of members 5, preformed so as to fit and fill the space between the head and base of the rail, and 40 with the members adapted to be progressively forced into the space with their confronting ends in abutting relation. In other words, the filler will extend continuously along the rail.

The material making up the composition 45 of the filler members should be selected for its inherent compressibility, waterproofing qualities and sound deadening qualities. To this end I would suggest that a composition 50 of asphalt and various kinds of fibrous material be used. The composition of the material is more or less immaterial so far as concerns my present invention, and for this reason I need not go into the details of the 55 same.

It so happens that it is rather inconven-

ient to mold or otherwise design the filler members so as to completely insulate the rail. However, to accomplish this object I have devised an insulating covering 6 for the 60 members, which preferably comprises a waterproof felted sheet, the same being applied to the members, and due to the adhesive nature of the asphalt the covering will adhere when so applied. At any rate the 65 idea is primarily to use an excess amount of sheet covering so as to leave insulating aprons projecting from opposite horizontal edges from the members 5, so that these aprons may be turned up as at 8 and turned 70 down as at 7 to extend over the edges of the head and base of the rail and insulate the rail from the paving structure D.

By referring to Figure 1 it will be readily seen that with the construction described I 75 can completely insulate the rail from the paving material, so that not only is a waterproof joint made but the sound deadening qualities of the joint will be greatly improved, and this improvement also applies 80 to expansion and contraction.

As shown in Figure 2 the aprons may lie across the perpendicular outer surface of the members when the same are packed for shipment, and turned up as indicated by the 85 dotted lines when the members are applied to the rail.

The covering also acts as a reinforcement for the members and as it passes around the same it will insulate the members from the 90 rail. This is of no special importance except that it does increase the insulating qualities of the filler and holds the shape of the same, so that it is not so likely to ooze in hot weather nor crack and become brittle in 95 cold weather. These features are of more or less secondary importance compared to the idea of providing the insulating aprons. As illustrated in Figure 3 the covering need not be placed around the entire member but simply a strip 6^a applied along opposite horizontal edges of the members, so as to provide the insulating aprons as at 7 and 8. When occasion demands the space on both sides of the connecting web C may be filled 100 with the same material, although it would naturally be preformed or otherwise shaped to correspond to the dimensions and contour of the space.

I claim:

1. A rail filler of the class described, comprising a preformed block-like compressible

110

105

- member adapted to fill the space between the head and base of a track rail, and an insulating covering for one side of the block, the longitudinal edges of the covering extending beyond the longitudinal edges of the said block-like member and providing insulating aprons substantially as and for the purpose described.
2. A rail filler of the class described, comprising a preformed block-like compressible member adapted to fill the space between the head and base of a track rail, and a waterproofed sheet of felt covering one side of the block, the longitudinal edges of the covering extending beyond the longitudinal edges of the said block-like member and providing insulating aprons substantially as and for the purpose described.
3. A rail filler of the class described, comprising a preformed block-like compressible member adapted to fill the space between the head and base of a rail, and an insulating apron attached to and extending beyond opposite edges of the member substantially as and for the purpose described.
4. A rail filler of the class described, comprising a preformed block-like compressible member adapted to fill the space between the head and base of a rail, and an insulating apron of waterproofed felt attached to and extending beyond opposite edges of the member substantially as and for the purpose described.
5. In an imbedded track, a rail having a head, base and connecting web with a space between the head and base, a filler for said space, comprising preformed block-like compressible members, and insulating aprons projecting beyond the horizontal edges of the members and overlying the edges of the rail head and base for insulating the rail from the material in which it is imbedded.
6. In an imbedded track, a rail having a head, base and connecting web with a space between the head and base, a filler for said space, comprising preformed block-like compressible members, and insulating aprons projecting beyond the horizontal edges of the members and overlying the edges of the rail head and base for insulating the rail from the material in which it is imbedded, said aprons comprising the extended edges of a waterproof felt covering for the members.
7. In an imbedded track, a rail having a head, base and connecting web with a space between the head and base, a filler for said space, comprising preformed block-like compressible members, and insulating aprons projecting beyond the horizontal edges of the members and overlying the edges of the rail head and base for insulating the rail from the material in which it is imbedded, said aprons comprising the extended edges of a waterproof felt covering for the members, said covering also insulating the block-like members from the rail.

Signed at Chicago, Illinois, this 28th day of August, 1926.

ALBERT C. FISCHER.
